UNITED STATES PATENT OFFICE.

CARL EDWARD TANNEWITZ, OF GRAND RAPIDS, MICHIGAN.

INK-WELL.

1,116,758.

Specification of Letters Patent. Patented Nov. 10, 1914.

Application filed November 10, 1913. Serial No. 800,183.

To all whom it may concern:

Be it known that I, CARL EDWARD TANNEWITZ, a citizen of the United States, residing at Grand Rapids, Michigan, have invented certain new and useful Improvements in Ink-Well, of which the following is a specification.

This invention relates to improvements in ink wells.

10 The main objects of this invention are: First, to provide in an ink well, an improved receptacle holder which may be inserted in a hole or in a suitable support, such as a desk top. Second, to provide an improved ink well in which the receptacle is effectively sealed. Third, to provide an improved cover for ink wells by means of which the ink well is sealed and the parts are not liable to be affected by corrosion.

20 Further objects, and objects relating to structural details, will definitely appear from the detailed description to follow.

I accomplish the objects of my invention by the devices and means described in the 25 following specification.

The invention is clearly defined and pointed out in the claims.

A structure which is a preferred embodiment of my invention is clearly illustrated 30 in the accompanying drawing forming a part of this specification, in which:

Figure I is a detail perspective view of a structure embodying the features of my invention, a portion of a support being shown, the closure being shown in its open 35 position. Fig. II is a perspective view of the cover member. Fig. III is a perspective view of the receptacle holder removed from the support. Fig. IV is a detail vertical section on a line corresponding to line 4-4 of Fig. I. Fig. V is a horizontal section through the holder, on a line corresponding to line 5-5 of Fig. IV. Fig. VI is a perspective view of the closure member. Fig. VII is a detail vertical section on a line corresponding to line 7-7 of Fig. V.

In the drawing similar reference characters refer to similar parts throughout the several views, and the sectional views are 50 taken looking in the direction of the little arrows at the ends of the section lines.

Referring to the drawing, 1 represents a support such as the top of a desk, or the like.

55 The ink well receptacle holder consists of a barrel or body portion 2 formed of a

piece of sheet metal rolled into cylindrical form and having lugs 3 struck out from its sides to engage the support, as shown in Fig. IV, the lugs being pointed and directed 60 upwardly.

The top member 4 of the holder is provided with an outwardly projecting rim 5 at its upper end adapted to rest on the top of the desk or to be countersunk therein as 65 desired, and with an inwardly projecting flange 6 at the bottom constituting a support for the ink receptacle 7, the receptacle being provided with an outwardly projecting flange 8 at the top resting on the flange 70 as shown in Fig. IV. The top member 4 is, in practice, drawn or formed by means of suitable dies.

The flange 6 is slit at intervals and portions between the slits turned outwardly to 75 provide the securing tongues 9 which are arranged through horizontal slots in the barrel and clamped to secure the parts together, as shown in Figs. III, V and VII.

The edges of the barrel are left free and 80 turned outwardly slightly to provide spring support engaging members, there being a securing tongue adjacent to each edge of the barrel, as shown in Fig. V.

The cover member 10 is provided with a 85 downturned flange 11 at its edge closely fitting within the top member 4 and embracing the flange on the upper end of the receptacle 7. See Fig. IV.

The cover member is provided with an 90 upwardly offset cylindrical housing 12 in its top for the disk-like closure member 13. The top of the cover member is provided with a pen opening 14, while the closure member is provided with an opening 15 95 adapted to be brought into register with the opening 14.

The housing is provided with a slot 16 in one side through which the finger piece 16 of the closure member projects. The 100 ends of the slot constitute stops for the closure member.

The closure member is supported and retained in its housing by the disk 18 fitted into the flange on the cover member and 105 resting upon the upper end of the receptacle to seal the same. The closure member 13 is preferably formed of non-corroding material, hard fiber being preferred, while the disk 18 is preferably formed of non-corroding 110 material, a paraffined or oiled cardboard being preferred. This effectively seals the

ink receptacle and the parts do not become corroded and thereby destroyed or rendered inoperative.

The disk 18 is provided with an opening 5 registering with the opening 14 in the cover member. The lower end of the barrel 2 is preferably turned inwardly, as shown, to assist in entering into the hole in the support and also to provide smooth edges for 10 the parts which project into the disk.

When it is desired to remove the receptacle, the cover is pushed out by pushing up on the bottom of the receptacle. The holder is effectively retained in the desk or 15 support so that it cannot be conveniently removed without the aid of tools.

My improved ink well is simple and economical in structure and easily assembled in its support and projects but little 20 above the top of the desk even when not countersunk. It is obvious that it can be readily countersunk into the desk.

I have illustrated and described my improvements in detail in the embodiment preferred by me. I have not attempted to illustrate or describe certain modifications in structural details, as the disclosure made will enable those skilled in the art to which my invention relates to embody or adapt the 25 same as conditions may require. I desire, however, to be understood as claiming my improvements specifically in the form illustrated, as well as broadly within the scope of the appended claims.

Having thus described my invention, what 30 I claim as new and desire to secure by Letters Patent is:

1. In an ink well, the combination of a receptacle having an outwardly projecting flange at the top; a holder comprising a barrel member; a top member having an outwardly projecting rim at the top and an inwardly projecting flange at the bottom arranged within said barrel member and outwardly turned securing tongues formed 40 from said flange, disposed through slots in the barrel member, the receptacle being arranged within the holder with its flange resting on the bottom flange of said top member; a cover member having a downturned flange at its edge telescoping into said top member and embracing the flange of the receptacle, the top of said cover member having a central cylindrical closure 45 housing offset upwardly therefrom, said housing having a slot in one side and a hole through its top; a disk-like closure member having an opening adapted to be brought into and out of register with said opening 50 in said cover as it is rotated in said housing, and a finger piece disposed in said slot in said housing, the ends of the slot constituting stops for the finger piece; and a disk fitted within said cover to retain the closure 55 disk in its housing and having an opening 60 in said cover as it is rotated in said housing, and a finger piece disposed in said slot in said housing, the ends of the slot constituting stops for the finger piece; and a disk fitted within said cover to retain the closure 65 disk in its housing and having an opening 70

therein registering with said opening in said cover member.

2. In an ink well, the combination of a receptacle having an outwardly projecting flange at the top; a holder comprising a barrel member; a top member having an outwardly projecting rim at the top and an inwardly projecting flange at the bottom arranged within said barrel member and outwardly turned securing tongues formed 75 from said flange disposed through slots in the barrel member, the receptacle being arranged within the holder with its flange resting on the bottom flange of said top member; and a cover member having a downturned flange at its edge telescoping into said top member and embracing the flange of the receptacle, said cover member having an opening in its top. 80

3. In an ink well, the combination of a receptacle having an outwardly projecting flange at the top; a holder comprising a barrel member; a top member having an outwardly projecting rim at the top and an inwardly projecting receptacle support 85 and integral securing tongues disposed through slots in said barrel member; a cover member having a downturned flange at its edge telescoping into said top member and embracing the flange of the receptacle, the top of said cover member having a central cylindrical closure housing offset upwardly therefrom, said housing having a slot in one side and a hole through its top; a disk-like closure member having an opening adapted to be brought into and out of register with said opening in said cover as it is rotated in said housing, and a finger piece disposed in said slot in said housing, the ends of the slot constituting stops for the finger piece; and a disk fitted within said cover to retain the closure disk in its housing. 90

4. In an ink well, the combination of a receptacle having an outwardly projecting flange at the top; a holder therefor comprising a cylindrical member having supports engaging said receptacle flange; a cover having a downturned flange at its edge telescoping into said holder member and embracing the flange of the receptacle, the top of said cover member having a central cylindrical closure housing offset upwardly therefrom, said housing having a slot in one side and a hole through its top; a disk-like closure member having an opening adapted to be brought into register with said opening in said cover and a finger piece disposed in said slot in said housing, the ends of the slot constituting finger piece stops; and a disk fitted within said cover to retain the closure disk in its housing and resting upon the top of said receptacle. 105

5. In an ink well, the combination of a receptacle; a holder therefor; a cover for said holder, the top of said cover member having 110

5 a cylindrical closure housing offset upwardly therefrom, said housing having a slot in one side and a hole through its top; a disk-like closure member of hard fiber having an opening adapted to be brought into register with said opening in said cover member and a finger piece disposed in said slot in said housing; the ends of the slot constituting finger piece stops; and a disk fitted within 10 said cover member to retain the closure disk in its housing and resting upon the top of said receptacle to seal the same, said disk being formed of moisture proof cardboard, all coacting for the purpose specified.

15 6. In an ink well, the combination of a receptacle; a holder therefor; a cover member having a downturned flange at its edge telescoping with said holder and having an opening in its top; a disk-like closure member of non-corrosive material having an opening therein adapted to be brought into register with said opening in said cover member rotatably mounted on said cover member; and a disk fitted within said cover 20 member flange to retain the closure disk and resting upon the top of said receptacle to seal the same, said disk being formed of non-corrosive material and having an opening therein registering with said opening in 25 said top, all coacting for the purpose specified.

30 7. In an ink well, the combination of a receptacle; a holder therefor; a cover member having a downturned flange at its edge telescoping with said holder, the top of said cover member having a central cylindrical closure member housing offset upwardly therefrom and having a hole in its top; a disk-like closure member having an opening 35 adapted to be brought into register with said opening in said cover; and a disk fitted into said cover flange against the under side of the cover to retain the closure disk in its housing and having an opening therein registering with said 40 opening in said cover top.

45 8. A holder for ink well receptacles comprising a barrel member formed of a piece of sheet metal rolled into cylindrical form; and a cylindrical top member having an outwardly projecting rim at the top and an inwardly projecting receptacle supporting flange at the bottom arranged within said barrel member, said flange being slotted at intervals, the parts between the slits being turned outwardly to provide securing 50 tongues disposed through slots in the barrel, there being a tongue adjacent each edge of the barrel member.

55 9. A holder for ink well receptacles comprising a barrel member and a top member disposed within said barrel and having an

outwardly projecting rim at the top and an inwardly projecting receptacle supporting flange at the bottom arranged within said barrel member and having securing tongues 65 formed from said flange and turned outwardly and disposed through slots in the barrel member whereby the barrel is supported; and a cover member having a down-turned flange at its edge telescoping into 70 said top member so that the edge of the cover is substantially flush with the top flange of the top member.

10. A holder for ink well receptacles comprising a barrel member formed of a piece 75 of sheet metal rolled into cylindrical form; a cylindrical top member having an inwardly projecting receptacle supporting flange at the bottom arranged within said barrel member and having integral securing 80 tongues arranged through slots in the barrel member; and a cover having a downwardly projecting flange at its edge telescoping into said top member.

11. A holder for ink well receptacles comprising a barrel member formed of a piece of sheet metal rolled into cylindrical form, a cylindrical top member to which said barrel member is secured, a cover member having a downturned flange at its edge telescoping 90 with said top member, the top of said cover member having a central cylindrical closure member housing offset upwardly therefrom and having a hole in its top; a disk-like closure member having an opening adapted 95 to be brought into register with said opening in said cover, and a disk fitted into said cover flange against the under side of the cover to retain the closure disk in its housing and having an opening therein registering with 100 said opening in said cover top.

12. A holder for ink well receptacles comprising a barrel member formed of a piece of sheet metal rolled into cylindrical form, a cylindrical top member having an outwardly 105 projecting flange at the top, said top member and barrel member being provided with coengaging tongues and slots whereby they are secured together, a cover member having a downturned flange at its edge telescoping with said top member so that the edge of the cover is substantially flush with the flange of the top member, a disk-like closure member, and a retaining disk fitted into 110 said cover flange to retain the closure disk.

In witness whereof, I have hereunto set my hand and seal in the presence of two witnesses.
